(57) **CLAIM**

The ornamental design for a computer cover, as shown and described.

DESCRIPTION

FIG. 1 is a right side perspective view of a computer cover showing my new design;

FIG. 2 is a left side perspective view thereof;

FIG. 3 is a top plan view thereof;

FIG. 4 is a bottom plan view thereof;

FIG. 5 is a side elevational view thereof; and,

FIG. 6 is a front elevational view thereof.

The computer cabinet is shown in broken lines for illustrative purposes only and forms no part of the claimed design.
